(57) **CLAIM**

The ornamental design for a mini ski exerciser, as shown and described.

DESCRIPTION

FIG. 1 is a front-right-top perspective view of a mini ski exerciser, showing my new design;

FIG. 2 is a front elevational view thereof;

FIG. 3 is a rear elevational view thereof;

FIG. 4 is a right elevational view thereof, the left side being a mirror image thereof;

FIG. 5 is a top plan view thereof; and,

FIG. 6 is a bottom plan view thereof.
